(57) CLAIM

The ornamental design for a custom food branding iron, as shown and described.

DESCRIPTION

FIG. 1 is a perspective view of the custom food branding iron, showing the new design;

FIG. 2 is a front elevational view of the custom food branding iron thereof;

FIG. 3 is a rear elevational view of the custom food branding iron thereof;

FIG. 4 is a left side elevational view of the custom food branding iron thereof;

FIG. 5 is a right side elevational view of the custom food branding iron thereof;

FIG. 6 is a top plan view of the custom food branding iron thereof;

FIG. 7 is a bottom plan view of the custom food branding iron thereof; and,

FIG. 8 is a exploded perspective view of the custom food branding iron thereof.

The broken lines in the drawings illustrate environmental subject matter and form no part of the claimed design.
